KNITTING METHOD AND MACHINE

Wilbur L. Houseman, South Orange, N. J., assignor
to Standard-Trump Bros. Machine Co., Laconia,
N. H., a corporation of Delaware

Application March 30, 1934, Serial No. 718,197

27 Claims.

(Cl. 66—36)

This invention relates to a knitting method and machine and has particular reference to the production of selective normal and reverse plating by needle deflection.

5 In my application Ser. No. 209,383, filed July 29, 1927, there is disclosed a method and machine for knitting selectively normal and reverse plated fabric. In accordance with the disclosure of said application, the needles as they are drawn down to draw stitches over the sinkers are selectively left in normal position or deflected inwardly, whereby the positions of the yarns are either maintained in normal relationship or are reversed, thereby giving rise to selective stitches 10 in which the order of the yarns differs. In accordance with said application, there are provided in association with the various needles pressers which are acted upon by jacks carrying various arrangements of butts, which jacks are 15 pushed inwardly when needle deflection is to occur in a selective fashion depending upon the actuation of butt engaging levers and the positions of the butts upon the jacks.

The mechanism just referred to is perfectly 20 adapted for the purpose of producing selective plating and reverse plating, but unless the number of butts on the jacks is increased to an objectionable extent which would not only take up an undue amount of space, but which would 25 give rise to objectionable lateral thrust on the jacks, there is a definite limit to the character of patterns which may be produced. It is the broad object of the present invention to provide a selecting method and means for securing deflection of needles at desired times which is 30 adapted for the production of elaborate patterns involving numerous variations in needle selection.

Other objects of the invention, particularly 35 relating to details of construction and manipulations, will be apparent from the following description read in conjunction with the accompanying drawings, in which:

40 Fig. 1 is a diagrammatic vertical section taken 45 on the plane indicated at 1—1 in Fig. 3 through a needle cylinder and associated parts illustrating certain elements used in accordance with the invention;

50 Fig. 2 is a diagrammatic fragmentary inside development of the needle cams and latch ring and associated parts showing the taking of yarns by needles;

55 Fig. 3 is an inside development of various needle, jack and associated cams;

Fig. 4 is a diagrammatic plan view showing certain cam controlling means;

Fig. 5 is a horizontal section showing controlling devices for effecting selection;

Fig. 6 is a fragmentary elevation showing the same subject matter as Fig. 5; and

Figs. 7, 8 and 9 are sections similar to Fig. 1 but taken on planes indicated at 7—7, 8—8 and 9—9, respectively, in Fig. 3.

The knitting machine which is specifically 10 illustrated for the purpose of showing the invention is, in general, of conventional character and only so much of the machine is illustrated as is necessary for a clear understanding of the invention. The machine comprises an elongated 15 rotary needle cylinder 2, rotated through the medium of a ring gear 4, which cylinder is provided with the usual slots 6 for the reception of needles and other associated parts. The needles are of the usual latch type and are provided with 20 butts 10 and shoulders 12 located, as illustrated, above the butts. In order to produce reverse plating, the upper ends of the needles are adapted to be flexed inwardly, while at the same time, as 25 is desirable, the lower ends of the needles are maintained in proper position within the needle slots without being carried outwardly. In order to provide for the deflection of the upper ends of the needles the upper end of each slot is deepened to provide a shoulder 14 above which the upper 30 end of the needle may be deflected inwardly, the deflection being limited by engagement of the needle with the upper portion of the bottom of the deepened portion of the slot as indicated in Fig. 7. Deflection of a needle is accomplished by 35 the use of a presser 16, which is provided with an outwardly extending shoulder 17 and engages the needle at two locations, above and below the shoulder 14 at 18 and 20 respectively, the inner 40 edge of the presser being cut away between these places. Each presser is adapted to rest upon the shoulder 12 of the needle at proper times as later described and is provided with a butt 22 which may be engaged by a suitable cam which causes 45 the presser to move downwardly. When the presser is in its uppermost position, spring bands 24 of the variety usually used for holding needles within their slots, engage the pressers above and below outward projections indicated at 26. The projection associated with each presser by 50 engagement between the spring bands serves to yieldingly retain the presser in its uppermost position. The presser may, however, be forcibly moved downwardly by engagement of a cam with its butt so that both of the spring bands may be 55

above the projection 26 as indicated for example in Fig. 9.

Rotating outside the needle circle in the usual fashion is the sinker dial 28 in which the sinkers

- 5 30 are guided for their usual inward and outward movements between the needles by suitable cams, this action occurring in conventional fashion.
- 10 Slidable in suitable slots in the sinker dial are jacks 32 which are aligned with the needle slots so that each of them on its inward movement may engage the shoulder 17 of a presser if the presser occupies its raised position. In this case the jack may move the presser sufficiently inwardly to cause the upper end of the needle to 15 be deflected inwardly and thus produce reverse plating. However, if the presser is in its lower position, then inward movement of the jack corresponding thereto will move above the shoulder 17 and will be ineffective to deflect the needle.
- 20 Each jack is provided with a plurality of butts 34 in the present embodiment of the invention, although, as will be described later, it is sometimes necessary to provide only a single butt, the butts not being used in general for selectivity in 25 the production of designs. The various jacks are lightly held inwardly by the use of a spring band 36 which, however, does not exert upon them such force as would cause them to deflect the needles.
- 30 Located in the needle slots below the needles are intermediate jacks 38 provided with butts 40, while below these intermediate jacks are located lower tilting jacks 42 whose inner edges are so formed as to provide a pivot 44 about which, as a 35 horizontal axis, the jacks may rock. At their lower ends the jacks 42 are provided with shoulders 46 adapted to engage cams, as will be hereinafter more fully pointed out. The jacks are also provided below their pivots with butts 48 40 which may be selectively arranged for the purpose of producing patterns. The jacks may be supplied, for example, containing a full complement of butts which may be selectively broken out in order to provide the necessary setup for a 45 desired pattern.

Referring to Fig. 3, there is disclosed the layout of cams arranged to act upon the needles, jacks 32, the butts of the pressers, and the intermediate and lower jacks 38 and 42. The needle 50 stitch cams are of the usual variety and comprise the upper center cam 50 and the usual stitch drawing cams 52 and 54, the former of which serves to draw the needles downwardly during rotary knitting.

55 Cooperating with the lower jacks there are an upper cam 56 designed to rock the lower ends of the jacks outwardly, and a series of lower cams 60 and 62 designed to rock the lower ends of the jacks inwardly. All of these cams are formed as 60 levers and will be referred to hereafter. The lowermost of the cams designed to rock the jacks inwardly is designated differently from the others, since it performs a somewhat different function.

65 In advance of the cams 60 there is located a fixed cam 58 which is designed to engage the shoulders 46 on the lower jacks and cause them to rise to a predetermined level before they reach the location of the cams 60. This action insures 70 a proper vertical alignment between the butts on the jacks and the various corresponding cams 60. There is also provided in a position following the cams 60 a cam 66 having an upward slope 64 on which the shoulder 46 of such of the jacks 42 75 as have their lower ends extending outwardly

may ride whereby such jacks will be raised. A slope 68 provided on the cam 66 serves to rock the lower ends of the jacks inwardly and thus disengage them from the top level of the cam 66. A guard cam 70 is provided to prevent possibility 5 of damage to the jacks during reciprocation and limit their downward movements.

A cam 72 is provided designed to engage the butts 22 of raised pressers so as to depress all of the pressers at its position. This is to prepare 10 the pressers for a subsequent selection.

Cams 74 and 76 are respectively designed to raise and lower needles by engagement with their butts 10 for purposes which will hereafter become apparent. The lower action of cam 76 is continued by the usual guard cam 78. A ring of cams indicated at 81 serves to maintain the intermediate jacks within their slots. A cam face 80 on the lower portion of this series is adapted to engage the butts 40 of the intermediate jacks to 20 lower them and with them the lower jacks 42.

Levers 82 and 84 are provided to act upon the butts of the horizontal sliding jacks 32. A cam 86 is provided to raise the needles to a desired 25 level. It may be noted that the loops on selected needles clear the latches just prior to cam 74 and the loops on unselected needles clear the latches thereof at cam 54.

The layout of cams having been described, there will now be referred to their controlling 30 means. The cams 82 and 84 have identical operating devices indicated in Fig. 4. These cams are formed on the ends of levers which are pivoted at 88 and are provided with tails 90 carrying cam surfaces 93 held in engagement with actuating 35 ends of levers 94 by springs 92. Each of the levers 94 is provided with an elongated slot 96 receiving a vertical pin 98 and is urged by an individual spring 102 into engagement with an adjustable fixed stop screw 100. By this arrangement, as will be obvious, there is provided a fine adjustment of the position of the levers 94 and hence of the positions of the cam ends 82 and 84. Very fine adjustment is here necessary, in view of the fact that such adjustment determines 40 the extent to which fine gauge needles may be deflected inwardly, which should be to contact with the bottom of the needle slot as mentioned above without strain on the needles by too much deflection. Each of the levers 94 is connected by 45 a link 104 to a lever 106. The levers 106 are secured to nested vertically extending shafts which carry at their lower ends cam following levers 108 engageable under the action of springs 102 with suitable controlling cams 110 on the 50 main cam drum 111, which is stepped about under chain control during the operation of the machine in the usual fashion. The butts of the jacks 32 lie approximately in the circle indicated at 112, while the needle circle is indicated, for 55 comparison, at 114. The cams 74 and 76 are moved radially together and are carried by a sliding plunger 116 guided in a fixed portion of the machine and urged outwardly by a spring 118 into engagement with an adjustable stop 60 screw 120 carried by the end of a lever 122 which is urged counterclockwise, as viewed in plan, by a spring 124 stronger than the spring 118.

The cam 72 is carried by a similar plunger 126 urged outwardly by a spring 128. The plunger 70 126 is moved inwardly at the proper time by a clockwise movement of a cam 130 on a lever 132. The levers 122 and 132 are mounted upon vertically extending nested shafts which, at their lower ends, carry cam following levers 136 and 75

138 engageable with suitable cams 140 carried by the pattern drum 111.

Control of the cams 60, which are formed as levers pivoted at 141, is effected by the action upon tails thereof of tricks carried by a trick-wheel 142. These tricks, which are receivable in slots in the trick-wheel in the usual fashion, are provided with butts which may be selectively arranged to produce the desired control of the cams 60. The trick-wheel 144 is stepped about intermittently by the action of a pawl 146 which is oscillated through the medium of a link 148 by the lever 150, which rides upon lugs carried by the links of a pattern chain 152, which is advanced one step upon each revolution of the needle cylinder. By a suitable setup of the lugs on the pattern chain the trick-wheel may be advanced upon each revolution of the needle cylinder or at less frequent intervals. A guard 154 is provided for interrupting the advance of the trick-wheel and for securing a setup thereof at the completion of a stocking, this being effected as described in the application of Stanley R. Shelmire, Ser. No. 623,057, filed July 18, 1932.

25 The cam 56 is formed on a lever which has a functionally integral but adjustable extension 156 connected by a link to a lever 158 which is secured to one of a series of vertical nested shafts whose lower ends carry cams acted upon by cams 30 on the pattern drum 111.

If desired the series of cams 60 may operate in a plurality of sets. In the machine illustrated, for example, there are three such sets. By reason of such arrangement, there is made a convenient provision for the formation in a single stocking of three quite different and independent patterns in different portions thereof. For example, besides a usual normal and reverse plated pattern extending throughout the stocking, provision may be made for the formation of a clock or the like extending through only a portion of the design. The groups of levers may be selectively rendered operative or inoperative by control of levers 160 which engage their rear ends and pull them away from the tricks on the trick wheel 142 against the action of the springs 161. The levers 160 are independently controlled by links 162 connected to arms on three of the nested shafts heretofore referred to.

50 The lowermost cam 62, which is also pivoted at 141, is controlled by a connection through a link 164 to an arm carried by still another of the nested shafts. The yarns which are to be selectively normal and reverse plated are fed to the needles in conventional fashion, for example, by being fed through individual openings in a yarn finger 9 forming one of a plurality adapted to feed the yarns through an opening 11 in a latch ring 7. If yarn changes are to be made, pairs 55 of yarns are carried by various fingers which may be selectively brought into operation at predetermined times by the usual yarn changing mechanism.

The operations involved in producing normal 60 and reverse plating by the mechanism just described will be readily understood from a consideration primarily of Figs. 1, 3, 7, 8 and 9. In Fig. 3 there are indicated in dotted lines the paths of characteristic parts of the various elements associated with the needles in the needle slots and the needles themselves. For example, at *a* and *b* there are indicated the alternative paths of the needle butts. At *c* and *d* there are indicated the alternative paths of the butts 22 of the pressers 70 65 75 16. At *e* and *f* there are indicated the alternative

paths of the shoulders 46 of the lower jacks 42 and at *g* and *h* there are indicated alternative paths of the butts 40 of the intermediate jacks 38. It will be noted that through the greater part of the needle circle the butts of the needles and intermediate jacks and the shoulders of the lower jacks follow constant paths. 5

Initially, let it be assumed that a needle is to pass through a cycle in one revolution in which it will not be deflected. Starting with the needle 10 slot in a position just prior to the point where the jack therein would be engaged by the cam 56, the corresponding jack will have its lower end located in the inner position. However, as soon as the position of the cam 56 is reached, 15 the lower end of the jack will be thrown outwardly so that it will ride up the cam 58 to a position in which its butts would be properly lined up with the actuating cams 60. Since the needle associated with this jack is not to be deflected 20 during the next stitch forming operation, one of the butts of the jack will be engaged by a cam 60 which is allowed to move inwardly by the action of the trick-wheel so that the lower end of the jack will be located in a position wherein 25 it will not engage the cam 64. As a consequence, the shoulder 46 of the jack will follow the path indicated at *e*. During the rising movement over the cam 58 the jack 42 will have slightly raised its jack 38, whose butt will follow the path indicated at *g*. The intermediate jack, however, will not have been raised to a sufficient extent to engage the needle. 30

If in the preceding revolution of the needle cylinder the presser 16 has been raised, then as 35 it reaches the location of the cam 72 its butt would be engaged thereby with the result that the presser would be depressed to an extent bringing its shoulder 17 below the level of the radially sliding jack 32. The butt 22 of the presser will 40 thereafter follow the path *c*.

Since the needle was not engaged by the intermediate jack, its butt will move at the level *a* passing under the cam 74. Thereafter it will 45 pass through the usual knitting wave but will not be deflected, since although one of the cams 82 or 84 will move the jack 32 inwardly, the end of this jack will pass above the shoulder 17 without engaging the presser 16.

It will be noted that the intermediate jack will 50 be engaged and slightly depressed by the action of the cam 80, forcing the lower jack downwardly to a corresponding extent.

The above describes the series of operations involved in the manipulation of the parts associated with the needle which is not deflected. There will now be described a similar series of events in connection with a needle which is to be deflected to produce a reverse plated stitch. 55

Again, an outer position of the shoulder 46 60 of the lower jack is insured by the action of the cam 56 and the jack consequently rides upwardly due to the action of the cam 58 into position wherein its butts are aligned with the various cams 60. In this case, however, none of the cams will engage any of the butts and therefore as the jack approaches the cam 64 its shoulder will engage the cam and will follow the path indicated at *f*. As the lower jack moves upwardly, the intermediate jack is pushed upwardly so 70 that its butt follows the path *h*. As the intermediate jack approaches its maximum height, it engages the needle and moves it upwardly to such extent that its butt will engage the cam 74 and consequently follow the path indicated 75.

at *b*. Prior to this, if the presser had been in upper position, it would be depressed by the action of the cam **72**. As the needle rises as indicated at *b*, its shoulder **12** will engage the presser, moving it upwardly so that its butt will follow the path indicated at *d*, with the shoulder **17** now aligned with the jack **32**. Immediately after raising the presser, the needle is depressed by the cam **76** and later by the guard cam **78**, whereupon it passes through the knitting cams in the conventional wave. As the stitch is being drawn, the needle will now be deflected by reason of the engagement of the shoulder **17** of the presser by the jack **32**. In view of the formation of the presser, the needle is engaged both above and below the shoulder **14**, and consequently deflection takes place without any tendency of the lower end of the needle to move outwardly from the slot. The deflection of the needle during the stitch drawing operation serves to effect reverse plating in the well known fashion.

From the above it will be obvious that the proper preselection of elements insures the production of either normal or reverse plating in the next stitch drawing operation. It is to be noted that the action of the cams **60** is somewhat negative in the sense that reverse plating is effected when none of the cams engages a lower jack.

It is frequently desirable to interrupt the formation of patterns in order to knit what is known as a plain sole. If the sole needles are associated with jacks provided with butts in alignment with the cam **62**, then if this cam is caused to be continuously in operative position during the formation of the foot portion of the stocking, normal plated knitting will be effected on the sole needles. At the same time, selective actuation of the jacks associated with instep needles may proceed as in the knitting of the leg, the jacks associated with these latter needles having the butts capable of cooperating with the cam **62** removed.

Alternatively the production or non-production of reverse plating may be controlled by a selection of cams **82** and **84** cooperating with a predetermined arrangement of butts **34** on the jacks **32**. Usually, however, both of these cams may be continuously operated or, if desired, only one need be provided. They may, however, be used not only for producing a plain sole or similar wide band of normal plating, but may be associated with a predetermined setup of butts on the jacks and selectively controlled to effect the production of a checked design on which may be superimposed the more elaborate patterns effected by control of the lower jacks. In view of the fact that the control of the lower jacks is primarily depended upon for production of patterns, it is usually unnecessary to provide any large number of butts **34**. However, if desired, more than two of these may be used, the selection then proceeding along the lines of my prior application referred to above in addition to that accomplished through the medium of the lower jacks.

The various cams **72**, **74**, **76**, **82** and **84** are made movable primarily for withdrawal during heel and toe knitting and also for purposes of leveling and transfer, the movability of cams **82** and **84** being provided to prevent the deflection of needles during the transfer operation in addition to their movability, if desired, for selectivity.

It will be observed from the above that there

is provided a method and machine whereby selectivity of a high degree may be attained for the production of very elaborate patterns. This is due not only to the provision of multiple butt jacks **42**, but also to the groupings of the cams **60** whereby any one of a plurality of groups may be rendered active to control the jacks. Additionally, as pointed out above, control may be achieved through selective action of cams upon the jacks **32** which actuate the pressers. The trick-wheel, furthermore, need not be stepped about uniformly, but an irregular motion may be imparted thereto by the proper setup of the chain **152**. An enormous variety of patterns can thus be achieved with a compact patterning means of simple form so that setup for the production of any desired pattern is readily effected.

It will be clear that various changes in the specific embodiment of the invention may be made without departing from the scope thereof as defined in the following claims.

What I claim and desire to protect by Letters Patent is:

1. A circular knitting machine including a needle cylinder, needles slideable in said cylinder, means cooperating with the needles for the formation of stitches, elements individually associated with at least certain of said needles and slideable in said cylinder into alternative positions, means cooperating with the elements at one location in the formation of a course whereby needles may be selectively deflected dependent upon the positions of the elements associated therewith, and means acting at a prior location to selectively slide said needles to thereby effect selective positioning of said elements. 25

2. A circular knitting machine including a slotted needle cylinder, needles slideable in these slots of said cylinder, means cooperating with the needles for the formation of stitches, slideable pressers associated with at least certain of said needles and carried by the needle cylinder, radially slideable members arranged to engage pressers by inward movements when the pressers are located in proper position to effect deflection of the needles associated therewith, and means for moving needles associated with pressers at a prior location whereby the pressers associated therewith may be selectively positioned, said last named means including jacks movable in the needle slots below the needles, and means for selectively actuating said jacks. 40

3. A circular knitting machine including a slotted needle cylinder, needles slideable in the slots in said cylinder, means cooperating with the needles for the formation of stitches, vertically slideable pressers individually associated with at least certain of said needles and carried by the needle cylinder, radially slideable members arranged to engage pressers by inward movements when the pressers are raised whereby said pressers are caused to deflect their needles, said radially slideable members failing to engage pressers in lowered position, and jacks movable in the needle slots below the needles and adapted to position said pressers. 55

4. A circular knitting machine including a slotted needle cylinder, needles slideable in the slots in said cylinder, means cooperating with the needles for the formation of stitches, vertically slideable pressers individually associated with at least certain of said needles and carried by the needle cylinder, radially slideable members arranged to engage pressers by inward movements when the pressers are raised whereby said 70

pressers are caused to deflect their needles, said radially slideable members failing to engage pressers in lowered position, intermediate jacks slideable in the needle slots below the needles, 5 lower jacks slideable and also pivotable in the needle slots below the intermediate jacks, said lower jacks being provided with suitably arranged butts, cams selectively actuatable to engage said butts to rock the lower jacks, means for controlling the last mentioned cams, means arranged to raise lower jacks which are not rocked by the last mentioned cams whereby they raise the intermediate jacks, needles and pressers associated therewith, so that the needles are deflected by the 10 pressers.

5. A circular knitting machine including a slotted needle cylinder, needles slideable in the slots in said cylinder, means cooperating with the needles for the formation of stitches, vertically 20 slideable pressers individually associated with at least certain of said needles and carried by the needle cylinder, means arranged to engage pressers to move them inwardly when the pressers are raised whereby said pressers are caused to 25 deflect the needles, said means failing to engage pressers in lower position, and means acting upon the needles to cause them to position the pressers at a point prior to that at which the presser engaging means acts.

30: 6. A circular knitting machine including a needle cylinder, needles slideable in said cylinder, means cooperating with the needles for the formation of the stitches, elements individually associated with at least certain of said needles and 35 movable into alternative positions, means cooperating with the elements at one location in the formation of a course whereby needles may be selectively deflected dependent upon the position of the elements associated therewith, means at a 40 prior location for causing all of said elements to assume a predetermined position, means for selectively raising needles at an intermediate location to thereby selectively position said elements, and means for thereafter causing said 45 needles to pass through their usual knitting wave.

7. The method of producing selective reverse plating by needle deflection including feeding a plurality of yarns to a circular series of needles and moving said needles to produce stitches, acting upon elements individually associated with at 50 least certain of said needles to cause them to selectively deflect the needles dependent upon their position, and selectively positioning said elements at a prior location by causing selective movements of needles thereat.

8. The method of producing selective reverse plating by needle deflection including feeding a plurality of yarns to a circular series of needles and moving said needles to produce stitches, 55 acting upon elements individually associated with at least certain of said needles to cause them to selectively deflect the needles dependent upon their position, and selectively positioning said elements at a prior location by causing selective movements of those needles which are to be deflected.

9. A circular knitting machine including a needle cylinder, needles slideable in said cylinder, yarn feeding means, elements individually associated with at least certain of said needles and movable into alternative positions, means cooperating with the elements adjacent the yarn feeding position to effect the production of various characters of stitches depending upon the position of the elements, and means for selectively 70

moving needles at a prior location to thereby effect selective positioning of said elements.

10. A circular knitting machine including a needle cylinder, needles slideable in said cylinder, yarn feeding means, elements individually associated with at least certain of said needles and movable into alternative positions, means cooperating with the elements adjacent the yarn feeding position to effect the production of various characters of stitches depending upon the 10 position of the elements, means at a prior location for causing all of said elements to assume a predetermined position, and means for selectively moving needles at an intermediate location to thereby effect selective positioning of said 15 elements.

11. A circular knitting machine including a needle cylinder, needles slideable in said cylinder, means for feeding a plurality of yarns to the needles, elements individually associated with at least certain of said needles and movable into alternative positions, means cooperating with the elements adjacent the position where yarns are being drawn to form loops to effect the production of normal or reverse plating depending upon 25 the position of the elements, and means for selectively moving needles at a prior location to thereby effect selective positioning of said elements.

12. A circular knitting machine including a 30 needle cylinder, needles slideable in said cylinder, means for feeding a plurality of yarns to the needles, elements individually associated with at least certain of said needles and movable into alternative positions, means cooperating with the 35 elements adjacent the position where yarns are being drawn to form loops to effect the production of normal or reverse plating depending upon the position of the elements, means at a prior location for causing all of said elements to assume a 40 predetermined position, and means for selectively moving needles at an intermediate location to thereby effect selective positioning of said elements.

13. A circular knitting machine including a 45 needle cylinder, needles slideable in said cylinder, means for feeding a plurality of yarns to the needles, elements individually associated with at least certain of said needles and movable into alternative positions, means cooperating with the 50 elements adjacent the position where yarns are being drawn to form loops to effect the production of normal or reverse plating depending upon the position of the elements, means at a prior location for causing all of said elements to assume a predetermined position, means for selectively moving needles at an intermediate location to thereby effect selective positioning of said elements, and means for thereafter causing said 55 needles to pass through their usual knitting wave. 60

14. A circular knitting machine including a needle cylinder, needles slideable in said cylinder, yarn feeding means, jacks individually associated with at least certain of the needles, means for imparting movements relative to the needle cylinder to at least certain of said jacks during the formation of all of certain courses, independently movable elements associated with the jacks, and pattern means for selectively positioning said elements so that said movements of said jacks 65 may or may not be operative to effect the production of various characters of stitches in the aforementioned courses.

15. A circular knitting machine including a needle cylinder, needles slideable in said cylinder, 75

- yarn feeding means, means operative adjacent to the yarn feeding means to effect the production of various characters of stitches, means for selectively positioning needles at a prior location to 5 affect the second named means to determine the character of stitches to be produced, means for thereafter causing said needles to pass through their usual knitting wave, and means for operating the second named means at the point where 10 the needles pass through their knitting wave to thereby effect the production of stitches of the character predetermined.
16. A circular knitting machine including a slotted needle cylinder, needles slideable in the 15 slots of said cylinder, means cooperating with the needles for the formation of stitches, elements associated with at least certain of said needles adapted to be acted upon at the stitch drawing position to effect selective production of various 20 characters of stitches, and means for selectively moving needles in advance of the stitch drawing position to position their associated elements to later effect said selective stitch production.
17. A circular knitting machine including a 25 needle cylinder, needles slideable in said cylinder, yarn feeding means, pressers associated with at least certain of said needles, means for moving pressers radially at one point to flex needles after the pressers are located in one of a plurality of 30 alternative axially differentiated positions, and pattern mechanism for selectively so positioning the pressers at a prior point.
18. A circular knitting machine including a 35 needle cylinder, needles slideable in said cylinder, yarn feeding means, pressers associated with at least certain of said needles, means for moving pressers radially to flex needles at the yarn feed point after the pressers are located in one of a plurality of alternative axially differentiated 40 positions, and pattern mechanism for selectively so positioning the pressers prior to the yarn feeding point.
19. The method of producing selective reverse plating by needle deflection including feeding a 45 plurality of yarns to a circular series of needles and moving said needles to produce stitches, operating relatively to the needle cylinder, in the formation of every course involving reverse plating, jacks associated with at least certain of said needles, and selectively moving pressers interposed between said jacks and needles into operative or inoperative positions with respect to said 50 jacks prior to said operation of the jacks to effect selective deflection of the needles by the pressers through said operation of the jacks.
20. A circular knitting machine including a 55 needle cylinder, needles slideable in said cylinder, means cooperating with the needles for the formation of stitches, jacks associated with at least certain of said needles, means for operating at least certain of said jacks relatively to the needle cylinder in the formation of every course involving reverse plating, pressers interposed between said jacks and needles, and pattern means for 60 selectively positioning said pressers in operative or inoperative positions with respect to said jacks prior to said operation of the jacks to effect selective deflection of the needles by the pressers through said operation of the jacks.
21. A circular knitting machine including a 65 needle cylinder, needles slideable in said cylinder, yarn feeding means, jacks associated with at least certain of said needles, said jacks being continuously operated at the knitting point, 70 pressers individual to the needles slideable into alternative active and inactive positions relative to the jacks, said pressers being interposed between the jacks and their respective needles so that when the pressers are in one of said positions the jacks in their operation will impart a 5 needle flexing movement through the pressers, and pattern means to selectively cause the pressers to be placed in said alternative active or inactive positions relative to their jacks.
22. A circular knitting machine including a 10 needle cylinder, needles slideable in said cylinder, yarn feeding means, pressers associated with at least certain of said needles, said pressers being slideable in the needle slots outside the needles into alternative positions and being arranged to 15 flex the needles inwardly, jacks carried by the needle cylinder and arranged to engage the pressers only when the pressers are in one position to cause the pressers to flex their respective needles, and pattern mechanism for selectively locating the pressers in position to be so engaged by the jacks.
23. A circular knitting machine including a 20 needle cylinder, needles slideable in said cylinder, yarn feeding means, elements individually associated with at least certain of said needles, slideable in the needle slots, and movable into alternative axially differentiated positions, means adjacent the yarn feeding position mechanically 25 cooperating with the elements to effect the production of various characters of stitches depending upon the position of the elements, and means for so selectively alternatively positioning the elements at a point prior to the yarn feeding position to determine what will occur thereat.
24. A circular knitting machine including a 30 needle cylinder, needles slideable in said cylinder, yarn feeding means, elements individually associated with at least certain of said needles, slideable in the needle slots, and movable into alternative axially differentiated positions, means adjacent the yarn feeding position mechanically 35 cooperating with the elements, while they remain axially fixed, to effect the production of various characters of stitches depending upon the position of the elements, and means for so selectively alternatively positioning the elements at a point prior to the yarn feeding position to determine what will occur thereat.
25. A circular knitting machine including a 40 needle cylinder, needles slideable in said cylinder, yarn feeding means, elements individually associated with at least certain of said needles, slideable in the needle slots, and movable into alternative axially differentiated positions, radially 45 movable members individually associated with the elements, means for radially moving said members in the formation of each course so as to effect the production of various characters of stitches depending upon the position of the elements, and means for so selectively alternatively positioning the elements at a point prior to the yarn feeding position to determine what will occur thereat.
26. A circular knitting machine including a 50 needle cylinder, needles slideable in said cylinder, yarn feeding means, elements individually associated with at least certain of said needles, slideable in the needle slots, and movable into alternative axially differentiated positions, radially 55 movable members individually associated with the elements, means for radially moving said members in the formation of each course so as to effect the production of various characters of stitches depending upon the position of the elements, and means for so selectively alternatively positioning the elements at a point prior to the yarn feeding position to determine what will occur thereat.
27. A circular knitting machine including a 60 needle cylinder, needles slideable in said cylinder, means cooperating with the needles for the formation of stitches, slideable pressers associated with at least certain of said needles and carried by the needle cylinder, radially slideable members arranged to engage pressers by inward movements when the pressers are located in proper position to effect deflection of the needles associated therewith, and means for selectively mov- 70

ing needles associated with pressers to selectively position the pressers prior to the point where pressers may be engaged by said radially slidable members.

5 27. A circular knitting machine including a needle cylinder, needles slideable in said cylinder, yarn feeding means, pressers associated with at

least certain of said needles, means for moving pressers radially at one point to flex needles after the pressers are located in one of a plurality of alternative axially differentiated positions, and means for selectively moving needles to selectively 5 so position pressers at a prior point.
